UNITED STATES PATENT OFFICE.

HENRY ACKERMAN, OF WEEHAWKEN, NEW JERSEY.

DESIGN FOR A GEM-SETTING.

44,160.

Specification for Design.

Patented June 10, 1913.

Application filed March 18, 1913. Serial No. 755,255. Term of patent 14 years.

To all whom it may concern:

Be it known that I, HENRY ACKERMAN, a citizen of the United States, residing at Clifton Park, Weehawken, in the county of Hudson and State of New Jersey, have invented a new, original, and ornamental Design for a Gem-Setting, of which the following is a specification, reference being had to the accompanying drawing, forming part thereof, but in which the dotted lines form no part of the design.

Figure 1 is a plan view of a gem setting, showing my new design; and Fig. 2 is an edge view of Fig. 1.

I claim—

The ornamental design for a gem setting as shown.

HENRY ACKERMAN.
